UNITED STATES PATENT OFFICE.

WILLIAM O. ALDRICH, OF WHITINSVILLE, MASSACHUSETTS, ASSIGNOR TO THE WHITIN MACHINE WORKS, OF WHITINSVILLE, MASSACHUSETTS, A CORPORATION OF MASSACHUSETTS.

ROVING-CREEL.

1,156,451.

Specification of Letters Patent.

Patented Oct. 12, 1915.

Application filed September 9, 1908. Serial No. 452,298.

To all whom it may concern:

Be it known that I, WILLIAM O. ALDRICH, a citizen of the United States, residing at Whitinsville, county of Worcester, and 5 State of Massachusetts, have invented certain new and useful Improvements in Roving-Creels, of which the following is a full and true specification, such as will enable others skilled in the art to make, construct, 10 and use the same.

The invention is an improvement in roving creels for spinning and doubling frames, with the object to improve the durability and usefulness thereof, and consists in a 15 sheet metal construction of such apparatus, and in the combination, relative arrangement and construction of the several parts thereof whereby certain new and improved results are obtained, as hereinafter fully 20 described.

Referring to the drawings, Figure 1 is a vertical transverse section of a roving creel of a spinning frame embodying the invention; Fig. 2 is a side elevation of the same 25 mechanism with parts removed for clearness; Fig. 3 is a surface plan of a portion of the middle creel-board on enlarged scale; Fig. 4 is a section of Fig. 3 on line a—a 30 thereof; Fig. 4^a is a similar view of a modified form of board; Figs. 5 and 6 are respectively top plan and vertical section of a modified form of skewer bearing; Figs. 7 and 8 are similar views respectively of a further form of skewer bearing; and Figs. 35 9 and 10 are similar views, respectively, of a top holder according to this invention.

Referring to Figs. 1 and 2, the creel taken for illustration is a two-story creel comprising a base or bottom board 1, a middle board 40 2, and a top board 3. The bottom creel-board is supported on the cross-braces 4 which unite the roller beams 5, and is formed of sheet-metal, preferably in a single plate, with the central longitudinal area 45 thereof pressed or bent upwardly forming a central table somewhat elevated above the margins of the said board and above the level of the roller beams. The top and middle creel-boards are carried by intermediate uprights 6 and end uprights 7 mounted on the central table portion of the bottom board and are made of sheet metal 50 which is preferably formed of a single piece for each board, that is to say, of one plate

in the transverse direction, and each plate 55 is formed with marginal reinforcing flanges. In the case of the middle board, the reinforcing flanges, shown at 2^a, are turned downwardly, for convenience of access to the upper row of bobbins, and the flanges 60 of the top board are turned upwardly, as shown at 3^a, to form a trough or receptacle for extra skewers or bobbins. The ends of the top and middle creel-boards are supported on the adjustable sections of the end 65 uprights 7 while their intermediate portions are secured to the sliding sleeve brackets on the intermediate uprights 6, which arrangement permits vertical adjustment of the two upper boards in obvious manner in conformity with the height of the bobbin skewers of each story of the creel. The flanges on the two upper creel-boards and the upwardly pressed table portion of the bottom board respectively serve to stiffen these members 70 against the effect of vibration and adapt them to carry the load of the bobbins without sagging and likewise provide rounded edges to the creel boards which 75 safeguard the heavy bobbins from injury by contact with them. It is also advisable to press or form corrugations in the creel-boards, as shown for example in Fig. 4^a, wherein the corrugations are longitudinally disposed about midway between the center 80 and the marginal flanges,—all of which reinforcement permits relatively thin material to be employed for the creel-board plates, which is desirable for the fullest realization 85 of the benefits of the invention. The several creel boards are punched with a plurality of perforations 9 (see Fig. 3) some of which are adapted for receiving the step 90 bearings of the skewers and others of which serve to secure the holders for the tops of the skewers, and the arrangement of the steps and the top holders is such that no two bobbins on the same side of the frame 95 occupy the same vertical transverse plane.

The skewer steps of the form of the invention shown in Fig. 4 are pressed into their appropriate holes as indicated at 10 and held frictionally therein in a position in which their lower ends project somewhat below the bottom of the board so that they 105 are accessible from the underside thereof. In the form of Figs. 5 and 6, skewer-step 11 is formed with a head flange 12 which

supports the step by resting on the margin of the creel-board perforation 9, the lower extremity of the body of the step projecting downwardly beneath the bottom surface of the creel-board. A spring washer 13 provided with inwardly pointed spring fingers 13^a, embraces the projecting extremity of the step, engaging a slight ridge or base flange thereof, and forms releasable means 10 for locking the step against accidental displacement from its hole. In the form of Figs. 7 and 8 the skewer-step 14 is provided with a similar head flange, and a split spring ring 15 engages a groove in the body 15 of the step as the releasable means for locking it in place.

In each of the above forms of skewer-steps, the upper or bearing surface of the step though concaved to receive the skewer 20 is substantially flush with the top surface of the creel-board, so that they do not form receptacles for dirt, nor oppose the free 25 passage of the wiping brush. And in each case it will be noted, the skewer-step projects through the perforation in the relatively thin material of the creel board and depends considerably below the bottom surface thereof, which arrangement permits the 30 ready removal of any step when worn or broken, by simply pushing on it with the finger or by driving it upwardly with an appropriate instrument from underneath. At the same time, and particularly in the cases 35 of Figs. 6 and 8, the steps are secured against accidental displacement from vibration or other cause. These skewer-steps as shown in the drawing are usually made of porcelain, glass or similar vitreous and hence easily frangible material. For this 40 reason they are required to fit their perforations in the sheet metal plate with some looseness to keep them from becoming broken by the expansion of the sheet metal or their own expansion under changes of 45 temperature. The spring securing rings engaging with their projecting bottoms, hold the steps as thus mounted, from accidental dislodgment without exerting injurious pressure upon them.

50 The skewers S bearing their bobbins B are vertically seated in the skewer-steps constructed and mounted as above described, and as shown in Figs. 1 and 2, and the upper extremities of the said skewers are supported within top holders which project from the under side of the upper boards. According to my invention these holders 55 are hollow thimbles secured within certain of the perforations in the upper creel-boards and project downwardly therefrom for a distance of about three-quarters of an inch, or more than the thickness of the plates forming the creel-boards. In the form of top holder illustrated in Fig. 4 the thimbles, 60 designated 16, are frictionally held in their

perforations like the skewer-steps which in that figure are shown as being made of wood or fiber, and the lower orifices of said thimbles are flared and smoothed on the interior so that they provide a long bearing 70 affording easy entrance for the tops of the skewers and the least amount of wear as the latter revolve therein. In its preferred form, the thimble 17, forming the top holder, has the form of a rather large eyelet, as shown in Figs. 9 and 10, which is upset or expanded at its head within the perforation, and further held in position by means of a bottom flange which is bent upward into engagement with the metal of 75 the creel board. This flange may be variously disposed, but it is most suitably formed by reversely bending the lower end of the thimble as shown at 17^a, until the edge thereof meets the bottom of the creel board. 80 The bearing thus provided for the skewer tops is devoid of cutting edges and has the flaring orifice above mentioned, and when constructed as shown, the top-holders do not interfere with the cleansing of the creel 85 boards, although they, or the skewers in them, may project somewhat above the said boards. The length of the thimbles or top holders, however, is such that a comparatively rough adjustment of the creel boards 90 will still permit some considerable variation in the length of the different skewers on each story, and this adjustment is facilitated by the fact that the creel-boards are not subject to warping, as in the case of 95 wooden creels, and hence remain at all times substantially flat. The yarn guides 18 are carried on brackets 19 as usual, fixed to the middle creel board.

It is included within my invention to 100 provide apertures or open spaces in the creel board between the rows of skewer steps and top holders, or, if desired, to form the said creel boards of independent metallic sheets of the appropriate thinness, for the purpose 105 of lightening the construction, but I prefer that the creel-boards shall present continuous surfaces as above described, both on account of the convenience in cleansing them of oil and lint and as a protection to the 110 inner mechanism from injury by skewers or bobbins dropping into the interior of the frame.

Having described my invention, what I claim and desire to secure by United States 115 Letters Patent is:

1. In a creel, the combination of a perforated sheet metal creel-board having down-turned flanges on its opposite margins, tubular top-holder thimbles secured in some of the perforations therein and skewer-steps of porcelain seated in the other of said perforations and loosely confined therein against dislodgment.

2. In a spinning frame, a roving-creel,

comprising in combination, two sheet-metal plates forming the creel-boards, the upper of said plates being supplied with top-holder thimbles of greater length than the thickness of the plate and the lower plate being provided with corresponding skewer-steps inserted in perforations therein and provided with head flanges supporting said steps in the perforations with their bearing-surfaces substantially flush with the top of said plate and their bases projecting below the same, and means for adjusting the height of said upper creel-board plate above the lower plate.

15 3. In a roving-creel for spinning frames, an upper creel-board formed of a sheet-metal plate having a perforation therein, in combination with a top-holder thimble secured in registry with said perforation and forming a downward extension thereof, the lower extremity of said thimble being turned upwardly toward said sheet-metal plate and adapted to receive the skewer top.

4. In a creel, a perforated sheet metal creel-board and a skewer top holder consisting of a thimble seated in a perforation thereof and having an outwardly turned flange on its lower portion bent into engagement with the margin of said perforation.

30 5. In a creel, a series of superposed creel-boards, the middle one of which is formed of a sheet-metal plate of general rectangular form presenting a continuous smooth upper surface between its opposite longitudinal side margins, in combination with a plurality of skewer steps seated in perforations in said plate and a plurality of independent, tubular skewer top holders projecting downwardly from the under side of said plate.

40 6. In a roving creel, a series of superposed creel-boards, the middle one of which is formed of a flat sheet-metal plate of rectangular shape and having longitudinal side members providing rounded edges to said creel-board, in combination with a plurality of independent top-holder thimbles secured in projecting relation to said plate between said longitudinal side members and a plurality of skewer steps also seated on said plate.

50 7. In a creel, a horizontal sheet metal plate extending longitudinally of the creel constituting a creel board thereof and provided with a plurality of perforations, in combination with vitreous skewer steps supported within the said perforations free from lateral pressure against the walls thereof and having their upper surfaces all in substantially the same plane and their lower ends accessible to be ejected from the under side of the said plate.

60 8. A creel-board formed of a sheet metal plate having perforations extending entirely through it and skewer steps having body portions adapted to occupy said perforations

and head flanges adapted to rest on the margins of said perforations to support said body portions therein, and means engaging said body portions for retaining said steps against dislodgment.

70 9. In a creel, a sheet-metal creel-board having perforations extending entirely through the same and skewer-steps fitting said perforations, and projecting below the creel board, in combination with means co-acting with the under side of said creel-board and said projecting skewer-steps for locking the same in the said perforations.

75 10. In a creel the combination with a perforated sheet metal creel-board, of skewer-steps having head flanges supporting the same within the perforations in said plate and having their lower extremities projecting beneath the said creel board, and retaining means engaging said projecting extremities.

80 11. In a creel, a sheet metal plate forming a creel-board and provided with perforations through, the same, in combination with a plurality of vitreous skewer steps in said perforations having body portions formed with upper concave bearing surfaces and annular head flanges adapted to support said bodies in the aforesaid perforations with their said bearing surfaces substantially flush with said metal plate and their lower ends accessible from beneath the same.

90 12. In a creel, a sheet metal creel board having perforations extending through the same and porcelain skewer steps in said perforations having body portions loosely fitting the same and provided with upper concave bearing surfaces and with annular head flanges adapted to removably support said bodies therein, with their lower ends accessible from below said creel board, in combination with retaining means on the under side of said plate engaging said lower ends.

95 13. In a creel, a creel-board having a perforation extending through it, and a skewer step having a head flange adapted to support the same in said perforation and having a ridge or projection on its base or body portion and means engaging said ridge or projection to retain said step against dislodgement.

100 14. In a creel having superposed creel boards, a middle creel-board formed of a perforated sheet of metal, skewer-steps having head flanges seated on the margins of certain of said perforations, and top holder thimbles secured in the other of said perforations.

110 15. In a creel for spinning frames, a bottom creel-board supported between the roller beams and formed of sheet metal, having its central area pressed upwardly and forming an integral table elevated above the roller beam, uprights rising from said

upwardly pressed table and vertically adjustable creel-boards carried by said uprights.

16. In a spinning frame, a roving creel comprising in combination, two superposed sheet-metal plates forming the creel-boards, the lower of said plates being perforated and provided with a plurality of skewer steps supported free from lateral pressure therein and with their stop-surfaces in a common plane, and the upper of said plates having a plurality of top-holder thimbles secured in perforations in said plate and of greater length than the thickness of said plate, and means for adjusting the height of said upper plate above the lower plate.

17. In a spinning frame, a roving-creel comprising in combination upper and lower sheet-metal plates forming the creel-boards

and provided with a number of perforations through them, said upper plate having thimbles forming extensions of the perforations therein and adapted to receive the skewer-tops and said lower plate having skewer-steps supported in the perforations thereof free from lateral pressure and with their upper surfaces in a common plane adapted to support the bases of the skewers and means for adjusting the height of the upper plate above the lower one.

In testimony whereof, I have signed my name to the specification in the presence of two subscribing witnesses.

WILLIAM O. ALDRICH.
